TRAVELLING GRATE COMBUSTION OF COOKING
AND CAKING BITUMINOUS COALS

Carrington B. Phillips, Penn Valley, Pa.

Application June 8, 1956, Serial No. 590,328

1 Claim. (Cl. 110—69)

The present invention relates to methods and furnaces for burning coking and/or caking bituminous coals on travelling grate stokers. Most bituminous coals coke or cake at least slightly and many are strongly coking and/or caking, and their burning on travelling grate stokers ranges accordingly from troublesome to completely impractical.

When reference is made herein to travelling grate stokers it is intended to refer to stokers of the character which progress a thin fuel bed forward while maintaining the fuel bed quiescent. These are known variously as chain grate, travelling grate, oscillating grate, vibrating grate or moving grate stokers.

The purpose of the invention is to permit efficient and trouble-free burning of coking and/or caking coals on travelling grate stokers by preoxidizing the surface of the coal particles before combustion starts.

In the drawings I have chosen to illustrate one only of the numerous embodiments in which my invention may appear, selecting the form shown from the standpoints of convenience in illustration, satisfactory operation and clear demonstration of the principles involved.

Figure 1 is a central vertical longitudinal section of a travelling grate furnace in accordance with the invention.

Figure 2 is a section of Figure 1 on the line 2—2.

Describing in illustration but not in limitation and referring to the drawings.

Travelling grate stokers are, in many ways, superior to other types of stokers but must have a uniformly burning fuel bed. When coal cokes or cakes on travelling grate stokers, the resistance to the flow of combustion air through the fuel bed becomes irregular, the combustion is inefficient and the grates overheat because they are not protected by a uniform and compact bed of ash. Nevertheless travelling grate stokers are very desirable as they avoid all of the following difficulties, one or more of which are encountered in other stokers:

- (a) Fly ash which requires expensive collectors and which results in operation complications.
- (b) Excessive manual attention.
- (c) Troublesome clinkers.
- (d) Not readily adaptable to automatic operation.
- (e) Not readily adaptable to low-cost, shop-assembled boiler units.
- (f) High maintenance costs.
- (g) Not suitable for many of the smaller sizes of boiler units.

The present invention obtains a uniformly burning fuel bed on travelling grate stokers with coking and/or caking coals by preoxidizing the surface of the coal particles before furnace heat causes sticking together of the coal particles and after the coal bed has become quiescent.

It has been demonstrated that when preoxidizing air is passed through coal at a temperature of 200 to 500 degrees F. and the coal, therefore, is undisturbed before burning, all coking or caking will be eliminated.

2

It has also been demonstrated that preoxidizing of coal will not eliminate its coking or caking during combustion, if the coal is disturbed after preoxidizing and before combustion.

5 The present invention provides an arrangement for travelling grate stokers whereby preoxidation can take place within the limitations described in the preceding two paragraphs.

The invention provides, in connection with travelling 10 grate stokers, a separate fan connected to a compartment or zone, for preoxidizing air at a temperature of 200 to 500 degrees F., preferably between 200 and 400 degrees F., immediately behind the stoker hopper and gate and extending under and across the entire width of the grate and by providing an arch or other construction to shield the preoxidizing zone from the furnace heat.

In accordance with the invention coal 20, which may be coking and/or caking bituminous coal in slack or plus mesh sizes, is fed from a hopper 21 under a gate 22 to establish a coal bed 23 on a travelling grate 24 progressing in the direction of the arrow into the combustion chamber of a coal furnace. The coal bed as well known in the art will have a thickness of the order of 3 to 6 inches.

25 Immediately beyond the gate 22 the travelling grate carries the fuel bed above an air chamber 25 extending from side to side under the travelling grate, which receives air for preoxidation preheated in any suitable way to a temperature of 200 to 500 degrees F., preferably 200 to 400 degrees F. It will be understood that any desired preheating means can be used, whether a separate preheater, heated by furnace gas or by a separate source of heat, or a combined preheater and blower, as well known. I illustrate in Figure 2 a blower 26 supplying preheated air to the chamber 25. This may, if desired, be a preheating blower, a diagrammatic illustration of a preheater being shown at 26'.

The air passes up through the fuel bed at 27, encountering the fuel bed before the coal becomes plastic and has a tendency to stick together and while the coal particles are entirely separate and are thus all exposed to this air. To protect against too rapid heating of the fuel bed where preoxidizing is occurring, immediately beyond the gate 22 I provide a furnace wall or arch 28 whose lower side 30 hangs above the fuel bed and forms a protecting or shading arch. The arch is so close to the top of the fuel bed that there is only room for excess preoxidizing air to flow between it and the fuel bed. The lower side 30 desirably slopes upwardly gradually toward the furnace at an angle of 5 to 10 degrees to the horizontal.

55 The nose of the arch conveniently has a radius at 31.

In the preferred form of the invention the lower side of the shielding arch will be between 2 and 6 inches above the top of the fuel bed for a distance of 15 to 30 inches longitudinally of the stoker.

The excess preoxidizing air is deflected by the lower side of the arch at 32 to make it flow into the combustion chamber and mix with the furnace gases.

60 It will be understood that at a position beyond the preoxidizing zone the fuel bed receives the main combustion air which passes suitably upwardly at 33 under the action of a blower or the draft from a chimney, as well known.

65 In accordance with the invention therefore it is possible to burn coking and/or caking bituminous coals on a travelling grate in any desired coal size without additional precautions, as long as the preoxidizing is carried out as here described. Thus all of the advantages inherent in travelling grate stokers are made available in the case of coking and/or caking bituminous coals. For example, the more laborless operation of the stoker is

made possible. Fly ash is not produced and fly ash collectors are not required. Greater simplicity in operation results. The devices of the invention are adaptable for small boiler units and for "package units."

It will be evident of course that the device of the invention is not limited to coking and/or caking bituminous coals but can be used interchangeably where required for burning free-burning bituminous coals and also for burning lignite and sub-bituminous coals.

In view of my invention and disclosure variations and modifications to meet individual whim or particular need will doubtless become evident to others skilled in the art, to obtain all or part of the benefits of my invention without copying the method and apparatus shown, and I, therefore, claim all such insofar as they fall within the reasonable spirit and scope of my claim.

Having thus described my invention what I claim as new and desire to secure by Letters Patent is:

In a furnace for burning coking and/or caking bituminous coals, a travelling grate adapted to transport a fuel bed in quiescent condition, a hopper supplying coal to the grate, means for preheating air to a temperature between 200 and 500 degrees F., means for introducing the preheated air beneath the travelling grate to pass through the fuel bed immediately after the fuel bed is fed from the hopper and before the fuel bed enters distillation and combustion zones of the furnace,

an arch extending over the fuel bed for a length of from 15 to 30 inches longitudinally of the travelling grate and located between 2 and 6 inches above the top of the fuel bed, said arch extending above the position at which the preheated air is introduced, the lower side of said arch sloping upwardly toward the furnace at an angle of 5 to 10 degrees, said arch shielding the fuel bed from the intense furnace heat, whereby the fuel bed derives all of its heat immediately after it leaves the hopper from the preheated air and is preoxidized so that it will not coke or cake in distillation and combustion zones which follow, and any excess of preoxidizing air will flow into and mix with the furnace gases.
